Primary Examiner—Sandra Snapp*Assistant Examiner*—Patricia Palasik(74) *Attorney, Agent, or Firm*—Andrus, Sceales, Starke & Sawall, LLP**CLAIM**

The ornamental design for a bacon comb, as shown.

DESCRIPTION

FIG. 1 is an isometric view of a bacon comb incorporating our new design;

FIG. 2 is front elevation view thereof;

FIG. 3 is a left side elevation view thereof;

FIG. 4 is a top plan view thereof;

FIG. 5 is a right side elevation view thereof;

FIG. 6 is a rear elevation view thereof; and,

FIG. 7 is a bottom plan view thereof.

The broken lines are for illustration only and form no part of the claimed design.
